UNITED STATES PATENT OFFICE

101,897

DESIGN FOR TABLE CLOTH OR SIMILAR ARTICLE

Francis J. Tausend, New York, N. Y.

Application July 18, 1936, Serial No. 63,916

Term of patent 7 years

To all whom it may concern:

Be it known that I, Francis J. Tausend, a citizen of the United States, residing in the Borough of Manhattan, city, county, and State of New York, have invented a new, original, and ornamental Design for Table Cloth or Similar Article, of which the following is a specification, reference being made to the accompanying drawings, forming part hereof.

In the drawings,

Fig. 1 is a plan view of a table cloth or similar article showing my new design,

Fig. 2 is a plan view of a portion of the table cloth shown in Fig. 1, illustrating the design within the blocks, which consists of alternating squares one having the appearance of a basket weave and the other a plain weave, with a finish in contrast with the background.

I claim:

The ornamental design for table cloth or similar article substantially as shown and described.
